UNITED STATES PATENT OFFICE.

MARIE PERILLAT, OF NEW YORK, N. Y., ASSIGNOR TO OVIDA COMPANY, INC., OF NEW YORK, N. Y., A CORPORATION OF NEW YORK.

DESIGN FOR A REDUCING-BRASSIÈRE.

50,702.

Specification for Design.

Patented May 1, 1917.

Application filed November 25, 1914. Serial No. 874,078. Term of patent 14 years.

To all whom it may concern:

Be it known that I, MARIE PERILLAT, a citizen of France, residing at New York, in the county of New York and State of New York, have invented a new, original, and ornamental Design for a Reducing-Brassière, (Case No. 527,) of which the following is a specification, reference being had to the accompanying drawings, forming part thereof, wherein—reducing brassière illustrating my new design; and

Fig. 2 a back perspective view.

I claim:

The ornamental design for a reducing brassière, as shown.

MARIE PERILLAT.
